CLAIM

The ornamental design for a cooler bag for solar LED speaker, as shown and described.

DESCRIPTION

FIG. 1 is a perspective view of the cooler bag for solar LED speaker shown with the main body bag removed for ease of illustration showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the cooler bag for solar LED speaker shown with the front, detachable pocket removed for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the cooler bag for solar LED speaker shown fully assembled, with the front detachable pocket attached to the main body bag.

The broken lines in the drawings depict portions of the cooler bag for solar LED speaker that form no part of the claimed design.
